UNITED STATES PATENT OFFICE.

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA.

WRAPPER-TABBING MECHANISM.

Application filed March 25, 1926. Serial No. 97,198.

My invention relates to mechanism for applying individual sheets, wrappers, labels or the like hereinafter generically termed "wrappers" provided with reinforcing or staying elements or tabs to cartons, containers, and particularly to boxes, and especially to unstayed boxes, hereinafter termed "boxes".

In accordance with my invention, in suitable adhesive-applying mechanism there is applied to an individual wrapper a coat of adhesive, as glue or equivalent, and, before the adhesive dries or sets, the wrapper is suitably conveyed into co-acting relation successively with mechanisms utilizable, respectively, for applying to the coated wrapper-surface reinforcing tabs or elements and for coating with adhesive the exposed tab surfaces, whereupon, before the adhesive coatings upon the wrapper and tabs dry or set, the individual tabbed wrapper is applied to a box by suitable mechanism, as a wrapping machine whereby the box is simultaneously stayed and wrapped.

More particularly in accordance with my invention, either or both of the tabbing and tab-coating operations aforesaid is or are effected without pause in the movement of the wrapper as it is conveyed from the adhesive-applying mechanism toward the wrapping machine.

Further in accordance with my invention, there are provided distinct units or mechanisms for effecting the various coating, tabbing and conveying operations, all of which operate in timed relation one with the other and with the wrapping machine.

My invention relates to one type of apparatus utilizable for performing the method disclosed in my prior application, Serial No. 81,175, filed January 14, 1926.

My invention resides in apparatus of the character hereinafter described and claimed.

For an illustration of one of the various forms my invention may take, reference is to be had to the accompanying drawing in which:

Fig. 1 is a side elevational view, partly in section, of apparatus constructed in accordance with my invention.

Fig. 2 is a side elevational view, partly in section, illustrating details of construction of the tabbing and tab-coating mechanisms.

Fig. 3 is a side elevational view, partly in section, showing a part of the tabbing mechanism illustrated in Fig. 2.

Fig. 4 is a plan view, certain parts omitted, of the apparatus illustrated in Fig. 2.

Fig. 5 is an enlarged side elevational view, partly in section, showing a wrapper-conveying mechanism receiving a wrapper from the adhesive-applying mechanism.

Fig. 6 is a plan view of the apparatus shown in Fig. 5.

Fig. 7 is an enlarged elevational view, partly in section, showing a coated tabbed wrapper at the time of its transfer to the conveying mechanism of the conveyor unit.

Fig. 8 is a side elevational view, partly in section, showing a wrapper-gripper comprised in the conveying unit.

Fig. 9 is a sectional view showing one manner of attaching a stencil to its supporting disk.

Fig. 10 is a sectional view illustrating one manner of supporting a wrapper as it is passed into co-acting engagement with the tabbing and tab-coating mechanisms.

Fig. 11 is a plan view of a wrapper having tabs applied thereto by mechanism herein disclosed.

Referring to the drawings and particularly Fig. 1, there is illustrated an adhesive-applying unit G, mechanism generically indicated at T for severing tabs, applying the severed tabs to an individual coated wrapper and applying adhesive to the exposed surface of the tabs, a conveying unit C, and a wrapping unit W.

The adhesive-applying unit G may be of any suitable type capable of applying adhesive to wrappers of box-wrapping paper, or other suitable material, and delivering the coated wrappers in succession preferably at uniform intervals. For example, the unit G may be of the same general type disclosed in Nitsch and Federwitz Letters Patent No. 1,472,614, granted October 30, 1923, or in Federwitz & Bailey application Serial No. 40,769, filed July 1, 1925, or in the Nitsch and Weightman application Serial No. 69-249, filed November 16, 1925.

The tabbing unit or mechanism T may be of the general character as disclosed, for example, in United States Letters Patent to Reifsnnyder and Schwertle, No. 1,060,026,

granted April 29, 1913, or to Nitsch, Weightman and Streeter, No. 1,451,782, granted April 17, 1923.

The conveying unit C may be of the same general character disclosed in the aforesaid Federwitz & Bailey application, No. 40,769, or in the Federwitz & Bailey application Serial No. 70,462, filed November 21, 1925.

The wrapping machine W may be of any suitable character, for example, as illustrated in the prior Letters Patent to Smith, No. 691,329, Nitsch & Federwitz, No. 1,540,900, or Federwitz & Bailey, Nos. 1,541,036 and 1,541,255.

15 *The adhesive-applying mechanism.*

In the example illustrated, the adhesive-applying unit G is of the same general type disclosed in the aforesaid Nitsch & Federwitz Letters Patent, No. 1,472,614. Unit G is driven at suitable speed by any suitable source of power and at predetermined intervals the suction roller 1 functions to deliver single wrappers S in succession from the stack 2 of unglued wrappers through the rotary feed roll mechanism designated generally at 3 into engagement with the glue distributing roll 4 which engages the glue drum 5 so mounted as to rotate with its lower surface immersed in adhesive contained in the receptacle 6. As well understood in the art, the glue distributing roll 4 by engaging the glue drum 5 has applied to its surface an adhesive coating which in turn is applied to individual wrappers as they are fed into engagement therewith through the rotary feed roll mechanism 3. As viewed in Fig. 5, the glue distributing roll 4 rotates in a counter-clockwise direction and carries the advanced edge of a wrapper S into engagement with the stripper members 6 which function to deflect the wrapper toward wrapper-gripping and conveying mechanism of a character hereinafter fully described.

15 *The sheet conveying mechanism for the tabbing apparatus.*

50 As viewed in Figs. 1 and 2, the side frames F of the adhesive-applying unit G extend upwardly above the coating mechanism comprised in said unit and are secured in suitable manner, as by the bolts 7, Fig. 2, to the side frames F¹ of the tabbing apparatus or mechanism, the latter comprising the transverse supporting or tying members 8.

Within the frames F, a shaft 9 journaled in the auxiliary pivotally-mounted frames f carries a pair of sprockets or the like 10 and 10^a, respectively, driving the chains, bands or equivalent 11 and 11^a passing over the idler sprockets 12 and 12^a mounted on a shaft 13 journaled in bearings in the frames

F¹ adjacent the receiving end of the conveying unit C.

Referring to Fig. 1, the shaft 14, mounted in bearings in the frame members F of the adhesive-applying unit, is the usual member 70 controlling intermittent step-by-step movement of the usual wrapper-conveying belt structure of such unit. Shaft 14, as well understood in the art, is rotated only during each cycle of operation of the adhesive-applying unit, and has heretofore been utilized to advance the belt structure of the unit just after a wrapper has left the glue-distributing roll and been deposited on said belt structure. Shaft 14 carries a gear 15 meshing with an idler gear 16, in turn meshing with an idler gear 17, which meshes with and drives a gear 18 keyed to the shaft 9 carrying the sprockets 10 and 10^a. Accordingly, for each cycle of operation of the adhesive-applying unit G, the upper and lower spans of the chains 11 and 11^a are advanced in the direction of the respective arrows, Fig. 1.

Chains 11 and 11^a in the example shown, 90 each carry a pair of wrapper-grippers which may be of any suitable character, for example, as shown in the aforesaid Federwitz and Bailey application, Serial No. 40,769. However, and as shown particularly in Figs. 5 and 6, each gripper V comprises a base member 19 carried by a link pin of the chain and a member 20 pivoted on the next adjacent chain link pin. Member 20 comprises an arm 21 and a gripper palm 22, 100 each biased in a counter-clockwise direction, Fig. 5, by a coil spring 23 or the like interposed between a portion of member 19 and the member 20. Wrapper-grippers V on the two chains 11 and 11^a are in transverse 105 alignment, and, in the example shown, with a gripper secured in position on one chain, the other gripper is so located on the same chain that the distance between them will be the same no matter in which direction 110 measurement is effected from the gripper first fixed in position.

Between the sprocket chains 11 and 11^a and suitably fixed in position are the members or abutments 24 and 25, Figs. 5, 6 and 7, 115 for actuating the pivoted members 20 of each gripper V to open the same. An abutment 24 carried by a member 24^a suitably secured to the transverse members of frame f is located adjacent each chain 11 and 11^a in 120 the path of arm 21 of each gripper V while a similar abutment 25, Fig. 7, suitably held in position by structure, not shown, is located in the path of arm 21 of each gripper V adjacent the receiving end of the conveyor unit C.

In Fig. 5, there is illustrated a gripper V in the position assumed thereby while the chain carrying the same is at rest. This gripper, and the one in transverse alignment 130

therewith, have been moved by their respective chains into such position that the abutments 24 by co-action with the arms 21 have functioned to move the gripper palms 22 from their respective base members 19. In such position, the two grippers remain at rest while the feed roll mechanism 3 advances the forward edge of a wrapper S thereinto. The timing of the machine is such that as the wrapper assumes the position indicated in Fig. 5, shaft 14, Fig. 1 is actuated and, through the train of gears described above, the upper spans of the chains are moved toward the right, Fig. 5. But slight movement is necessary to free arms 21 from abutments 24 whereupon palms 22 move into gripping engagement with the top surface of the wrapper whose bottom surface engages base members 19 and the wrapper is now transported toward the receiving end of the conveying unit C. Preferably, without pause in its journey, the coated wrapper is suitably reinforced or tabbed, and the exposed faces of the tabs covered with adhesive as hereinafter more fully described, and, as the wrapper is moved into engagement with the awaiting gripping mechanism at the receiving end of the conveying unit C, arms 21 of grippers V move into engagement with abutments 25 to release the coated tabbed wrapper, said grippers continuing their movement without pause until they reach the position indicated by broken lines at the lower right corner of Fig. 7 when rotation of shaft 14 is automatically discontinued and movement of the chains 11 and 11^a ceases. By this operation, it will be observed that the other pair of grippers V have been moved into the position of Fig. 5, and are now open and awaiting the delivery of another wrapper which will soon be advanced thereinto by the feed roll mechanism 3.

The frames f, Fig. 4, comprise a transverse member or rod 26 substantially in horizontal alignment with shaft 9 pivotally mounted in side frames F of the adhesive-applying unit G. Rotatably mounted on rod 26 are a number of spaced pulleys 27 on each of which is mounted a belt 28 or the like. Pulleys 29 secured to and driven by shaft 9 likewise receive the belts 28, which, accordingly, rotate during movement of chains 11 and 11^a and in the same direction to form a support movable with and at the same speed as that of the wrapper.

From the belts 28, the coated wrapper is carried by chains 11 and 11^a onto a plurality of bridging or guiding members 30 spanning the gap between belt 28 and the receiving end of the conveyor unit C. In the example shown, members 30 are supported on filler blocks 31, Fig. 10, in turn supported on the transverse tie members 8. By preference, the central member 30^a and its supporting

block are non-adjustably fixed in position on said members 8 while the outer members 30 are adjustably mounted for transverse movement with respect to frames F¹. To this end, tie members 8 may be slotted as indicated at 32, Figs. 4 and 10, and to hold members 30 in adjusted positions, handles or heads 33 may be actuated to thread screws 34 into recesses in blocks 31.

The tabbing mechanism.

A gear 35 intermittently rotated in timed relation with the adhesive-applying unit G drives a gear 36 keyed to a shaft 37 rotatable in bearings 38 mounted respectively on a frame F and a frame F¹, Figs. 1 and 2. A bevel gear 39 secured to shaft 37 meshes with and drives a corresponding bevel gear 40 keyed to a shaft 41 mounted in bearings in the frames F¹.

When the coated wrapper is to be tabbed or reinforced as indicated in Fig. 11, the tabs a and a¹ are applied by one tabbing mechanism while the tabs b and b¹ are applied by another tabbing mechanism. In the example illustrated, two tabbing mechanisms are mounted on shaft 41 and are duplicates or substantially so. Accordingly, a description of one will suffice for the other.

Referring to Figs. 2 and 3, there is illustrated a disk, wheel or the like 42 carrying duplicate tab-gripping mechanisms, each functioning to convey a tab into engagement with the coated wrapper transported by chains 11 and 11^a. As shown particularly in Fig. 3, each tab-gripping mechanism comprises a plate 43 adjustably secured to one side of disk 42 by a bolt 44 or the like passing through a circumferential T-groove or T-slot 44^a in the disk, the head of bolt 44 being confined within the wider slot portion from which it may be removed through a suitable enlarged opening, not shown. Plate 43 forms a bearing for a shaft or pin 45 to which is secured a member 46 having pivoted thereto a member 47 supporting the gripper finger 48, which at times co-operates with a member 49 for gripping a tab. A coil spring 50 or the like biases member 47 and finger 48 in a clockwise direction, Fig. 3. Member 46 comprises an arm 51 carrying at one end a roller 52 biased in a clockwise direction, Fig. 3, by a coil spring 53, or equivalent, seated in a recess in plate 43.

Secured in the T-shaped slot 44^a of disk 42 by bolts 44 adjacent each of the duplicate tab-gripping mechanisms are the gear segments 54 and cams 55. Also, secured in any suitable manner and in suitable position, as to the frames F¹ are the cams 56 and 57, which co-operate with the rollers 52 to move the arms 51 against the expansive force of springs 53 for opening the tab grippers.

Rising from the frames F¹ are the frame extensions f¹ supporting, one for each tab-

bing mechanism, a reel 58 on which has been wound a web or ribbon *w* of any material suitable for tabbing purposes, for example, a web or ribbon of paper of a grade heavier, 5 lighter or of a weight corresponding with the weight of paper (when paper is used) from which the wrappers *S* are formed. The tape *w* passes in succession over a tension roll 59 supported on a pivotal arm 60, thence 10 over the guiding rolls 61 and 62, and finally into engagement with the feed rolls 63 and 64 mounted on shafts having intermeshing gears 63^a and 64^a, Fig. 3. Feed roll 63 may be supported on a slideable member 65 en- 15 gaged by a trigger or the like 66 biased in a counter-clockwise direction, Fig. 2, by a coil spring 67 or the like confined on a rod 68 linked to trigger 66. Obviously, upon re-tracting trigger 66 against the expansive 20 force of spring 67, member 65 and roll 63 may be withdrawn toward the left, Fig. 2, whereupon the end of tape *w* may be passed below roll 64 and, when roll 63 and member 65 are replaced, the feeding mecha- 25 nism will be in operative condition.

A gear 69, keyed to the shaft carrying roll 64, meshes with a gear 70 rotatably supported in a suitable manner, as on a shaft having bearings in the frame extensions *f*¹, said gear 30 70 being alternately rotated through a part of a revolution by the gear segments 54, as hereinafter more fully described.

A rod 71 or the like pivoted to an arm 71^a in turn pivoted to a frame *f*¹ is mounted 35 for reciprocatory movement on said frame extension *f*¹ and may be moved alternately in an upward direction against the expansive force of a coil spring 72 or the like suitably confined on said rod, when cams 55 in succession engage a roll 71^b on arm 71^a. When rod 71 is thus moved, an arm 73 pivoted to rod 71 is swung in a clockwise direction, Fig. 2, to similarly rotate a shaft 74, whereby the end of an arm 75 is moved to- 40 ward the left, Fig. 2. In response to such movement of arm 75, sliding engagement is effected between the cutting elements 76 and 77, the former, in the example shown, being mounted in a stationary manner and the latter sliding on a plate 78.

Disk 42, by its driving connection de- 45 scribed above, is intermittently rotated in a counter-clockwise direction, Figs. 2 and 3.

The gear segment 54 comprised in one of 50 the tabbing mechanisms by co-action with gear 70 imparts rotative movement to roll 64 to feed the end of web *w* downwardly, as viewed in Figs. 2 and 3, a sufficient distance 55 so that the web portion lying below the cutting element 76 is of the proper tab length. After the web has been thus fed, cam 55 60 engages roll 71^b and imparts reciprocatory movement to rod 71, whereby cutter 77 is moved toward the left, Fig. 2, to sever the 65 tab.

Before the completion of the web-feeding operation aforesaid, fixed cam 56 has rocked arm 51 to move finger 48 from member 49, the position of the various parts being as indicated in Fig. 3. As the end of the web 70 *w* is fed downwardly, it is deflected by the curved end of plate 78 and assumes the position illustrated in Fig. 3, at which time the web is severed, as stated above. Immediately thereafter, roller 52 passes beyond cam 56 75 and spring 53 becomes effective to rotate arm 51 in a clockwise direction, Fig. 3, whereby finger 48 is snapped toward and into engagement with the tab now resting on member 49. Spring 50 is of comparatively light 80 weight, and when used, its primary function is that of permitting some relative movement of finger 48 and member 47 with respect to arm 51, whereby the shock of the impact between finger 48 and member 49 is absorbed 85 to some extent.

The foregoing operation occurs without cessation in the rotary movement of disk 42. In a similar manner, the other tabbing mechanism on disk 42 is automatically supplied with a tab, and the two tabbing mechanisms without pause of disk 42 deposit or secure the tabs to the coated surface of wrapper *S* while it moves from the left toward the right under the control of a pair 90 of transversely aligned grippers on the chains 11 and 11^a.

The parts are so timed that as the forward portion of the coated wrapper or the area thereof to which the tab *a*¹, for example, 95 is to be applied reaches a point substantially vertically below shaft 41, Fig. 2, roller 52 on arm 51 engages fixed cam 57 to release the tab from finger 48 and member 49. It is intended that the tab release shall occur just as the advanced tab edge engages the 100 coated surface of wrapper *S*, member 49, then, having the function of ironing or wiping the tab into engagement with the wrapper.

Continued movement of the coated wrapper toward the right, Fig. 2, brings the rear portion thereof into position for the application of the tab *a*, for example, which is applied in a manner similar to that described 105 above by the other tabbing mechanism on disk 42.

Obviously, by loosening the bolts 44, the tabbing mechanisms may be adjusted circumferentially of disk 42, to vary the regions 110 on the wrapper wherein the tabs are applied. It shall be understood, in the example shown and as stated above, that shaft 41 carries a similar disk 42 equipped with tabbing mechanisms in transverse alignment 115 with the similar tabbing mechanisms described above, to the end that tabs or reinforcing elements *b*¹ and *b*² may be applied to wrapper *S*.

After tabs *a*, *b*, *a*¹ and *b*¹ have been ap- 120

plied, the wrapper with its adhering tabs continues its movement toward the right, Fig. 2, and during such movement there is applied to the exposed tab surfaces a suitable 5 coating of adhesive.

The tab-coating mechanism.

Carried by the shaft 41 is a gear 79, Fig. 10 4, meshing with and driving an idler gear 80 rotatably mounted on a stub shaft 81 carried by one of the frames F¹, said gear 80 meshing with and driving a gear 82 keyed 15 to a shaft 83 extending transversely of and rotatably mounted in bearings in the frames F¹.

Gear 82 on shaft 83 meshes with and drives the idler gear 84 mounted on a stub shaft 85 in a frame F¹, the latter gear meshing with and driving the corresponding 20 idler gear 86 mounted on a second stub shaft 87 carried by said frame F¹, idler gear 86 meshing with and driving a gear 88 keyed to a shaft 89 carrying glue rolls 90, whose 25 lower surfaces are immersed in the adhesive or glue contained in a receptacle 91 mounted on a support 92 secured in suitable manner to the frames F¹.

Carried by the shaft 83 are a pair of disks 30 93, each in alignment longitudinally of the machine with a disk 42. In the example illustrated, disks 93 are duplicates or substantially so, and accordingly, a description of one will suffice for the other. Disk 93 is 35 provided with a circumferential groove 94 receiving, in the example shown, the flanged extremities of the frames of a pair of spaced stencils 95, each of which may be secured in a desired position circumferentially of 40 disk 93 by a bolt 96 or the like passing through the stencil frame and clamping a member or plate 97 to the disk periphery and also to the stencil, Fig. 9.

By the train of gears described above, 45 disk 93 and glue rolls 90 are rotated in unison with disk 42. Stencils 95, when moving with disk 93, are brought in succession into engagement with a glue roll 90 and have transferred to their outer curved surfaces 50 coatings of adhesive from said glue drum. It shall be understood that stencils 95 have been adjusted along the periphery of disk 93 in such manner that as the tabs on the wrapper pass a region vertically, or substantially so, beneath shaft 83, they are 55 engaged in succession by the outer curved surfaces of the stencils, with the result that there is applied to the exposed faces of such tabs a coating of adhesive. Disk 93, as 60 viewed in Fig. 2, rotates in a counter-clockwise direction, and it may be assumed, therefore, that one stencil co-acts with tab a¹ and the other stencil co-acts with the tab a, Fig. 11. It shall be understood that 65 the corresponding disk, not shown, similarly

co-acts with and coats in succession tabs b¹ and b, Fig. 11.

Under some circumstances, it may happen that stencils 95, besides coating the exposed faces of the tabs, have the added function of 70 effecting more intimate engagement between the tabs and the coated wrapper.

The bridging members 30, Fig. 4, may be suitably adjustable in directions transversely of the machine to form supports for 75 wrapper S in those regions thereof wherein the tabs are applied and coated as described above.

The foregoing tab-coating operation is performed without pause in the travel of the 80 coated tabbed wrapper toward the right, Fig. 4. After application of the adhesive coatings to the tabs, movement of the coated tabbed wrapper continues until it is released from the grippers V on chains 11 and 11^a 85 and substantially simultaneously deposited in the awaiting gripping mechanism at the receiving end of the conveying unit C, as hereinafter more fully described.

The wrapping machine W and conveying 90 unit O.

In the example illustrated, the wrapping machine W and the conveying unit C are of the same character illustrated in the 95 aforesaid Federwitz and Bailey application, Serial No. 40,769.

Referring to Fig. 1, the wrapping machine W comprises a pulley 98 driven by any suitable source of power, not shown, 100 and, when engaged by the slidable clutch member 99, under the control of a lever 100, rotary movement is imparted to the shaft 101 which controls a cam, not shown, to impart reciprocatory movement to the upper 105 form block structure 102, the latter, at pre-determined intervals, carrying a box and the wrapper to be applied thereto into engagement with the lower form block structure 103, both of said form block structures 110 then carrying the box and wrapper downwardly through the various tools and other instrumentalities comprised in the wrapping machine to wrap the box, as well understood in the art.

Connected to the shaft 101 in suitable manner, as by the plates 104, is the shaft 105 carrying a gear 106 meshing with and driving a gear 107 mounted on a shaft 108 journaled in bearings in the frames of the conveyor unit C. A cam 109 is likewise secured to shaft 108 and receives a roller 110 carried by an arm 111 pivotally mounted at one end on the frame of the conveyor unit C and at its other end carrying a gear quadrant 112 meshing with a gear 113 mounted on a shaft journaled in bearings in the upper frames of the conveyor unit. A gear 114 also secured to shaft 108 meshes with and drives a gear 115 secured at 115 120 125 130

one end to the shaft 116 having at its other end a gear 117 meshing with and driving a gear 118 mounted on a shaft 119 also rotatably supported in the upper frames of the conveyor unit.

As clearly described in the aforesaid Federwitz and Bailey application, Serial No. 40,769, the wrapping machine W and conveying unit C operate in synchronism, due 10 to the fact that the power for both is obtained from a common drive shaft comprising, in the examples shown, the shafts 101 and 105 tied or coupled together by the plates 104. Due to this arrangement the 15 wrapper feeding mechanism of the conveying unit C, which, as herein shown, comprises a pair of chains, bands or equivalent 120 and 120^a carrying transversely aligned grippers functions to deliver individual 20 wrappers in succession beneath the upper form block structure 102 when the latter is in its upper region of travel. To this end and as described in the aforesaid Federwitz and Bailey application, Serial No. 40,769, intermittent 25 movement of chains 120 and 120^a is effected by the gear quadrant 112, which, acting through gearing and other structure, not shown, and in timed relation with the reciprocating form block structure 102 functions 30 to effect step-by-step movement of said chains to intermittently deliver single wrappers below said form block structure 102, where they are held as by structure disclosed in said Federwitz and Bailey application, Serial No. 40,769, until the box to be wrapped is moved into engagement therewith.

One or more box-conveying bands, belts or the like 121, Fig. 1, continuously driven 40 by any suitable mechanism, not shown, are supplied with boxes B in any suitable manner and in single file move toward the wrapping machine W, each box in turn engaging the release mechanism 122 which is intermittently 45 raised in timed relation with the form block structure 102. After release of a box by the mechanism 122, belt 121 carries it toward the wrapping machine and, upon reaching the end of the belt, drops onto the box-pusher bars 123 which are reciprocated 50 in timed relation with the form block structure 102 to deliver the box therebeneath at substantially the same time that a wrapper is delivered by the chains 120 and 120^a. 55 When thus delivered, each box may be temporarily held, as by structure disclosed in said Federwitz and Bailey application, Serial No. 40,769, until disengaged by entrance 60 thereinto of the form block structure which carries the box downwardly into engagement with the wrapper and thence into co-acting relation with the various wrapping machine tools.

Chains 120 and 120^a are mounted, respectively, on sprockets 124, pairs of which are

carried at each end of the conveyor frames 125. Said chains may be equipped with any suitable type of wrapper-gripping mechanisms X. As shown, however, grippers X are of the character described in the aforesaid Federwitz and Bailey application, Serial No. 40,769, and comprise a plate bracket 126 carried by adjacent link pins of its supporting chain, said bracket forming a rotatable support for an edged wheel 127 or the like. Pivoted to one of said link pins is a member comprising an arm 128 and a palm 129, said member being biased in a clockwise direction as viewed in Fig. 7 by a spring or the like 129^a, Fig. 8. Chains 120 and 120^a each carry a plurality of the grippers X, pairs of which are in transverse alignment. The timing of the mechanism governing the intermittent movement of chains 120 and 120^a is such that successive 80 pairs of the grippers X stop with their arms 128, respectively, in engagement with the fixed cams 130 whereby the palms 129 are depressed and for an interval the grippers X remain stationary in open position. 90

While thus open, a pair of transversely aligned grippers V on chains 11 and 11^a transport the forward edge of a coated tabbed wrapper S between wheel 127 and palm 129, and, when substantially in the position indicated at the top of Fig. 7, arms 21 of grippers V engage abutments 25 whereupon the wrapper is released therefrom, movement of said grippers V continuing without pause until in the position indicated at the lower right corner of Fig. 7. 100

After the forward edge of the wrapper has been thus positioned in grippers X, movement of chains 120 and 120^a is initiated, the arms 128 immediately receding from cams 130 whereby the wrapper is gripped between palms 129 and wheels 127. Thereafter, step-by-step the tabbed coated wrapper is advanced toward the wrapping machine W, other tabbed coated wrappers being similarly fed by the grippers V into succeeding pairs of the grippers X. 110

Finally, the coated, tabbed wrappers individually and in succession arrive beneath the form block structure 102 substantially coincidentally with the arrival there of individual boxes B. Ordinarily, with mechanism of the character aforesaid the wrappers are applied to the box before material setting of the various adhesive coatings. This is true despite the fact that in the conveyor unit C the speed of wrapper movement may be relatively slower than while the wrappers are carried by chains 11 and 11^a. As well understood in the art, in the wrapping machine W, the boxes are wrapped in such manner that the tabs are applied around the box corners to thereby strengthen or reinforce the wrapped structure. 120

To the end that the adhesive-applying

unit G may be tripped or actuated at the proper times to cause a wrapper to be removed from stack 2, passed into engagement with the glue distributing roll 4 and 5 delivered by pairs of the grippers V into pairs of the grippers X while the latter are open and waiting at the receiving end of the conveyor unit C, a cam 131 is suitably positioned on shaft 119 which rotates but once 10 during each cycle of operation of the wrapping unit W. Cam 131, Fig. 1, once for each cycle aforesaid, engages a roller 132 carried by a pivoted arm 133 to which is secured one end of a rod, link or the like 15 134, secured at its other end to an arm 135, controlling oscillatory movement of a shaft 136 controlling the tripping mechanism of the adhesive-applying unit G.

Although I have illustrated and described 20 mechanism for applying tabs to an individual coated wrapper after passage thereof from the adhesive-applying mechanism, it shall be understood that my invention comprehends structure for applying tabs to 25 individual wrappers before passage thereof from said adhesive-applying mechanism, and more particularly, while stacked and before application of an adhesive coating to the wrapper, one face of which, however, 30 together with the exposed tab faces, should be immediately coated, preferably by the adhesive-applying mechanism, and thereafter suitably conveyed to a desired region where application to a box may be effected.

35 It shall also be understood that my invention is not to be restricted to the use of a conveying mechanism or the like for transferring the tabbed coated wrapper to a wrapping machine, nor need the tabbing or 40 adhesive-applying mechanisms either singly or jointly be synchronized or connected to the wrapping machine. For example, my invention finds an important application in those cases where the conveyor of the adhesive-applying mechanism delivers coated 45 tabbed wrappers in succession to the vicinity of a wrapping machine operating independently of the adhesive-applying mechanism, from which conveyor an operator may take 50 the wrappers one by one, register them on individual boxes and manually apply the box with the adhering wrapper to the wrapping machine from block structure.

What I claim is:

- 55 1. Wrapper-tabling mechanism comprising means for coating an individual wrapper with adhesive, means for applying tabs to the coated surface of the individual wrapper, and means for coating the exposed faces of said tabs with adhesive before setting of said first-mentioned adhesive coating.
- 60 2. Wrapper-tabling mechanism comprising means for coating an individual wrapper with adhesive, wrapper-tabling and tab-coating mechanisms, and means for convey-

ing the individual coated wrapper into co-acting relation successively with said mechanisms whereby tabs are applied to the coated wrapper surface and an adhesive coating applied to the exposed tab surfaces.

3. Wrapper-tabling mechanism comprising means for coating an individual wrapper with adhesive, wrapper-tabling and tab-coating mechanisms, and means for conveying the individual coated wrapper without 70 pause into co-acting relation successively with said mechanisms whereby tabs are applied to the coated wrapper surface and an adhesive coating applied to the exposed tab surfaces.

4. Wrapper-tabling mechanism comprising means for coating an individual wrapper with adhesive, means for applying tabs to the coated surface of the individual wrapper, and stenciling means for coating 85 the exposed faces of said tabs with adhesive before setting of said first-mentioned adhesive coating.

5. Wrapper-tabling mechanism comprising means for coating an individual wrapper with adhesive, means for applying tabs to the coated surface of the individual wrapper, and stencils successively engaging said tabs for applying adhesive thereto before setting of said first-mentioned adhesive coating.

6. Wrapper-tabling mechanism comprising means for coating an individual wrapper with adhesive, means for applying tabs to the coated surface of the individual wrapper, coating mechanism, and stencilling means engaging said coating mechanism and the box-engaging tabbed faces in succession for applying an adhesive coating to the latter before setting of said first-mentioned adhesive coating.

7. Wrapper-tabling mechanism comprising means for coating an individual wrapper with adhesive, means for applying tabs to the coated surface of the individual wrapper, and stencilling means for coating the exposed faces of said tabs during movement of the wrapper.

8. Wrapper-tabling mechanism comprising means for coating an individual wrapper with adhesive, means for applying tabs to the coated surface of the individual wrapper, and movable stencilling means for coating the exposed faces of said tabs during movement of the wrapper.

9. Wrapper-tabling mechanism comprising means for coating a wrapper with adhesive, wrapper-tabling and tab-coating mechanisms, and means comprising a chain for conveying the coated wrapper into co-acting 125 relation successively with said coating mechanisms whereby tabs are applied to the coated wrapper surface and an adhesive coating applied to the exposed tab surfaces.

10. Wrapper-tabling mechanism compris-

ing means for coating a wrapper with adhesive wrapper-tabbing and tab-coating mechanisms, and means comprising a plurality of chains carrying aligned wrapper grippers for conveying the coated wrapper into co-acting relation successively with said coating mechanisms whereby tabs are applied to the coated wrapper surface and an adhesive coating applied to the exposed tab surfaces.

11. Box-wrapping mechanism comprising means for securing tabs to an individual adhesive-coated wrapper, and means for applying the wrapper and tabs to a box while the tabs are soft or pliable as caused by said adhesive.

12. Box-wrapping mechanism comprising means for securing tabs to an adhesive-coated wrapper, a wrapping machine, and means for conveying the tabbed wrapper into the path of the form block structure of said machine before material setting of said adhesive.

13. Box-wrapping mechanism comprising means for securing tabs to an adhesive-coated wrapper, a wrapping machine, and means comprising intermittently movable wrapper-conveying mechanism for transporting the tabbed wrapper into the path of the form block structure of said machine before material setting of said adhesive.

14. Box-wrapping mechanism comprising means for securing tabs to an adhesive-coated wrapper, a wrapping machine, and means timed with said wrapping machine for conveying the tabbed wrapper into the path of the form block structure of said machine before material setting of said adhesive.

15. Box-wrapping mechanism comprising means for securing tabs to an adhesive-coated wrapper, a wrapping machine, and means comprising wrapper-conveying mechanism intermittently movable in timed relation with said wrapping machine for transporting the tabbed wrapper into the path of the form block structure of said machine before material setting of said adhesive.

16. Box-wrapping mechanism comprising means for securing tabs to an adhesive-coated wrapper, a wrapping machine, means for conveying a box into the path of the form block structure of said machine, and means for conveying the tabbed wrapper into said path before material setting of said adhesive.

17. Box-wrapping mechanism comprising means for securing tabs to an adhesive-coated wrapper, a wrapping machine, means timed with said wrapping machine for conveying a box into the path of the form block structure of said machine, and means likewise timed with said machine for conveying the tabbed wrapper into said path before material setting of said adhesive.

18. Wrapper-tabbing mechanism comprising

ing means for coating a wrapper with adhesive, means for applying tabs to the coated surface of said wrapper, means for coating the exposed faces of said tabs with adhesive, and conveying mechanism receiving the coated tabbed wrapper from said tabbing mechanism before material setting of said first-mentioned adhesive coating.

19. Wrapper-tabbing mechanism comprising means for coating a wrapper with adhesive, wrapper-tabbing and tab-coating mechanisms, means for conveying the coated wrapper into co-acting relation successively with said mechanisms whereby tabs are applied to the coated wrapper surface and an adhesive coating applied to the exposed tab surfaces, and conveying mechanism receiving the coated tabbed wrapper from said conveying means before material setting of said first-mentioned adhesive coating.

20. Wrapper-tabbing mechanism comprising means for coating a wrapper with adhesive, wrapper-tabbing and tab-coating mechanisms, means for conveying the coated wrapper without pause into co-acting relation successively with said mechanisms whereby tabs are applied to the coated wrapper surface and an adhesive coating applied to the exposed tab surfaces, and conveying mechanism timed with said conveying means receiving the coated tabbed wrapper before material setting of said first-named adhesive coating.

21. The combination with a wrapping machine, of wrapper-tabbing mechanism timed therewith for applying a plurality of tabs to individual wrappers.

22. The combination with a wrapping machine, of wrapper-tabbing mechanism timed therewith for applying tabs to moving individual wrappers in succession.

23. The combination with a wrapping machine, of wrapper-tabbing mechanism timed therewith for applying tabs to individual wrappers, each having a surface coated with adhesive.

24. The combination with a wrapping machine, of wrapper-tabbing mechanism timed therewith, means for coating a wrapper with adhesive, and means for conveying the coated wrapper into coating relation with said tabbing mechanism.

25. The combination with a wrapping machine, of wrapper-coating and tabbing mechanism timed therewith, and means likewise timed with said wrapping machine for conveying the coated wrapper from said coating mechanism into co-acting relation with said tabbing mechanisms.

26. The combination with a wrapping machine, of wrapper-coating, wrapper-tabbing and tab-coating mechanisms timed therewith, and means likewise timed with said wrapping machine for conveying the coated

- wrapper from said coating mechanism into co-acting relation with said wrapper-tabbing and tab-coating mechanisms.
27. The combination with a wrapping machine, of wrapper-coating, wrapper-tabbing and tab-coating mechanisms timed therewith, means likewise timed with said wrapping machine for conveying the coated wrapper from said coating mechanism into co-acting relation with said wrapper-tabbing and tab-coating mechanisms, and conveying mechanism receiving the coated tabbed wrapper from said conveying means and transporting the same into the path of the form block structure of the wrapping machine.
28. The combination with a wrapping machine, of wrapper-coating, wrapper-tabbing and tab-coating mechanisms timed therewith, means likewise timed with said wrapping machine for conveying the coated wrapper from said coating mechanism into co-acting relation with said wrapper-tabbing and tab-coating mechanisms, and conveying mechanism timed with the wrapping machine for receiving the coated tabbed wrapper from said conveying means and transporting the same into the path of the form block structure of the wrapping machine.
29. The combination with a wrapping machine, of wrapper-coating, wrapper-tabbing and tab-coating mechanisms timed therewith, means likewise timed with said wrapping machine for conveying the coated wrapper from said coating mechanism into co-acting relation with said wrapper-tabbing and tab-coating mechanisms, conveying mechanism timed with the wrapper machine for receiving the coated tabbed wrapper from said conveying means and transporting the same into the path of the form block structure of the wrapping machine, and means timed with the wrapping machine for conveying a box into said path.
30. In combination, mechanism for applying adhesive to individual wrappers in succession, means for applying tabs to the individual wrappers, and a conveyor for transporting the individual tabbed wrappers to a region removed from said mechanism.
31. In combination, mechanism for applying adhesive to individual wrappers in succession, means for thereafter applying tabs to the individual wrappers, and a conveyor for transporting the individual tabbed wrappers to a region removed from said mechanism.
32. In combination, mechanism for applying adhesive to individual wrappers in succession, means for thereafter applying tabs to the wrappers, means for coating the exposed faces of said tabs, and a conveyor for transporting the individual tabbed wrappers to a region removed from said mechanism.
33. In combination, mechanism for applying adhesive to wrappers, means for applying tabs to the individual wrappers, a conveyor for transporting the tabbed individual wrappers to a region removed from said mechanism, and means for coating the exposed faces of said tabs during movement of said conveyor.
34. In combination, mechanism for applying adhesive to wrappers, means for applying tabs to the individual wrappers, an endless conveyor for transporting the tabbed individual wrappers to a region removed from said mechanism, and means for coating the exposed faces of said tabs during movement of said conveyor.
35. The combination with mechanism for applying adhesive to wrappers in succession, of means for tabbing wrappers in succession, and conveyor structure for transporting the tabbed wrappers to a region removed from said mechanism before material setting of their adhesive coatings.
36. The combination with adhesive-applying mechanism, of means for applying tabs to wrappers in succession, means for coating the exposed faces of said tabs, and conveyor structure for transporting the tabbed wrappers to a region removed from said mechanism.
37. The combination with mechanism for applying an adhesive coating to an individual wrapper, of means for tabbing the individual wrapper, and means for transporting the individual tabbed wrapper to a region removed from said mechanism.
38. The combination with mechanism for applying an adhesive coating to an individual wrapper, of means for tabbing the individual wrapper after application of said adhesive coating, and means for transporting the individual tabbed wrapper to a region removed from said mechanism.
39. The combination with mechanism for applying an adhesive coating to an individual wrapper, of means for tabbing the individual wrapper, means for applying an adhesive coating to the exposed faces of the tabs, and means for transporting the individual tabbed wrapper to a region removed from said mechanism.
40. The combination with mechanism for applying an adhesive coating to an individual wrapper, of means for tabbing the individual wrapper, and means for transporting the individual tabbed wrapper to a region removed from said mechanism before material setting of said adhesive coating.
41. The combination with mechanism for applying an adhesive coating to an individual wrapper, of means for tabbing the individual wrapper after application of said adhesive coating, and means for transporting the individual tabbed wrapper to a region removed from said mechanism.

gion removed from said mechanism before material setting of said adhesive coating.

42. The combination with mechanism for applying an adhesive coating to an individual wrapper, of means for tabbing the individual wrapper, means for applying an adhesive coating to the exposed faces of the tabs, and means for transporting the individual tabbed wrapper to a region removed from said mechanism before material setting of said first-named adhesive coating.

43. The combination with a wrapping machine, of means for applying an adhesive coating to individual wrappers in succession, means timed with said wrapping machine for transporting the coated wrappers into the path of the wrapping machine form block structure, and means for tabbing the wrappers before arrival thereof in said path.

44. The combination with a wrapping machine, of means for applying an adhesive coating to individual wrappers in succession, means timed with said wrapping machine for transporting the coated wrappers into the path of the wrapping machine form block structure, and means for tabbing the wrappers while passing toward the wrapping machine.

45. The combination with a wrapping machine, of means for applying an adhesive coating to individual wrappers in succession, means timed with said wrapping machine for transporting an individual wrapper into the path of the wrapping machine form block structure before material setting of the adhesive coating thereon, and means for tabbing said wrapper before the arrival thereof in said path.

46. The combination with a wrapping machine, of means for applying an adhesive coating to individual wrappers in succession, means timed with said wrapping machine for transporting an individual wrapper into the path of the wrapping machine form block structure before material setting of the adhesive coating thereon, means for tabbing said wrapper before the arrival thereof in said path and means for coating with adhesive the exposed tab surfaces.

47. The combination with a wrapping machine and means timed therewith for de-

livering boxes in succession into the path of the wrapping machine form block structure, of means for applying an adhesive coating to individual wrappers in succession, means 55 timed with said wrapping machine for transporting the coated wrappers into the path of the wrapping machine form block structure, and means for tabbing the wrappers while passing toward the wrapping machine. 60

48. Wrapper-tabbing mechanism comprising means for coating individual wrappers with adhesive, means for conveying the individual coated wrappers in succession to a region removed from said coating means, 65 and tabbing mechanism adjustable transversely of the path of said coated wrappers for applying a plurality of tabs to individual wrappers.

49. Wrapper-tabbing mechanism comprising means for coating individual wrappers with adhesive, means for conveying the individual coated wrappers in succession to a region removed from said coating means, 75 and tabbing and tab-coating mechanisms 75 adjustable transversely of the path of said coated wrappers for applying a plurality of tabs to individual wrappers, and an adhesive coating to the exposed tab surfaces.

50. Wrapper-tabbing mechanism comprising means for coating individual wrappers with adhesive, means for conveying the individual coated wrappers in succession to a region removed from said coating means, 80 a supporting member, tabbing mechanism 85 carried thereby, and means for adjusting said tabbing mechanism circumferentially of said member.

51. Wrapper-tabbing mechanism comprising means for coating individual wrappers with adhesive, means for conveying the individual coated wrappers in succession to a region removed from said coating means, 90 a supporting member, tabbing mechanism carried thereby, means for adjusting said 95 tabbing mechanism circumferentially of said member, a second supporting member, tab-coating mechanism carried thereby, and means for adjusting said tab-coating mechanism circumferentially thereof.

JOHN S. STOKES.

gion removed from said mechanism before material setting of said adhesive coating.

42. The combination with mechanism for applying an adhesive coating to an individual wrapper, of means for tabbing the individual wrapper, means for applying an adhesive coating to the exposed faces of the tabs, and means for transporting the individual tabbed wrapper to a region removed from said mechanism before material setting of said first-named adhesive coating.

43. The combination with a wrapping machine, of means for applying an adhesive coating to individual wrappers in succession, means timed with said wrapping machine for transporting the coated wrappers into the path of the wrapping machine form block structure, and means for tabbing the wrappers before arrival thereof in said path.

44. The combination with a wrapping machine, of means for applying an adhesive coating to individual wrappers in succession, means timed with said wrapping machine for transporting the coated wrappers into the path of the wrapping machine form block structure, and means for tabbing the wrappers while passing toward the wrapping machine.

45. The combination with a wrapping machine, of means for applying an adhesive coating to individual wrappers in succession, means timed with said wrapping machine for transporting an individual wrapper into the path of the wrapping machine form block structure before material setting of the adhesive coating thereon, and means for tabbing said wrapper before the arrival thereof in said path.

46. The combination with a wrapping machine, of means for applying an adhesive coating to individual wrappers in succession, means timed with said wrapping machine for transporting an individual wrapper into the path of the wrapping machine form block structure before material setting of the adhesive coating thereon, means for tabbing said wrapper before the arrival thereof in said path and means for coating with adhesive the exposed tab surfaces.

47. The combination with a wrapping machine and means timed therewith for de-

livering boxes in succession into the path of the wrapping machine form block structure, of means for applying an adhesive coating to individual wrappers in succession, means 55 timed with said wrapping machine for transporting the coated wrappers into the path of the wrapping machine form block structure, and means for tabbing the wrappers while passing toward the wrapping machine. 60

48. Wrapper-tabbing mechanism comprising means for coating individual wrappers with adhesive, means for conveying the individual coated wrappers in succession to a region removed from said coating means, 65 and tabbing mechanism adjustable transversely of the path of said coated wrappers for applying a plurality of tabs to individual wrappers.

49. Wrapper-tabbing mechanism comprising means for coating individual wrappers with adhesive, means for conveying the individual coated wrappers in succession to a region removed from said coating means, 70 and tabbing and tab-coating mechanisms 75 adjustable transversely of the path of said coated wrappers for applying a plurality of tabs to individual wrappers, and an adhesive coating to the exposed tab surfaces.

50. Wrapper-tabbing mechanism comprising means for coating individual wrappers with adhesive, means for conveying the individual coated wrappers in succession to a region removed from said coating means, a supporting member, tabbing mechanism 85 carried thereby, and means for adjusting said tabbing mechanism circumferentially of said member.

51. Wrapper-tabbing mechanism comprising means for coating individual wrappers with adhesive, means for conveying the individual coated wrappers in succession to a region removed from said coating means, a supporting member, tabbing mechanism carried thereby, means for adjusting said tabbing mechanism circumferentially of said member, a second supporting member, tab-coating mechanism carried thereby, and means for adjusting said tab-coating mechanism circumferentially thereof. 95

JOHN S. STOKES.

Certificate of Correction.

Patent No. 1,611,693, granted December 21, 1926, to

JOHN S. STOKES.

It is hereby certified that error appears in the printed specification of the above-mentioned patent requiring correction as follows: Page 2, line 130, for the misspelled word "aliment" read *alignment*; page 8, line 2, claim 10, after the syllable "hesive" insert a comma; page 9, line 24, claim 28, for the compound word "tab-coating" read *tab-coating*; and that the said Letters Patent should be read with this correction therein that the same may conform to the record of the case in the Patent Office.

Signed and sealed this 1st day of March, A. D. 1927.

[*Seal*]

M. J. MOORE,
Acting Commissioner of Patents.
